TORQUE-INDICATING WRENCH

Willard C. Kress, Kenmore, N. Y., assignor to
 J. H. Williams & Co., Buffalo, N. Y., a corpora-
 tion of New York

Application March 18, 1937, Serial No. 131,547

1 Claim. (Cl. 265—1)

My present invention relates to a torque-indicating or measuring wrench, and aims to provide certain improvements thereon.

Torque-indicating or measuring wrenches have been heretofore proposed for indicating applied predetermined measured force in tightening cap-screws, bolts, nuts and the like in the various applications thereof and have recently found particular favor in the tightening of cap-screws and bolts for holding down the heads of engine cylinder blocks. These cylinder block heads are usually made of aluminum and are easily distorted. If the cap-screws or hold down bolts are not uniformly tightened, said cylinder heads are frequently ruptured where the cap-screws or bolts are to be severely tightened. In fact, many failures in motor rebuilding and cylinder block re-boring jobs have been definitely traced to the uneven tightening of the cylinder head studs.

20 The torque-indicating or measuring wrenches heretofore proposed with which I am familiar have either used springs or fluid pressure means for resisting and measuring the torque applied to the elements being rotated, and all are either complicated in construction or cumbersome and unwieldy in use.

My present invention provides a torque indicating wrench consisting of but a few parts and devoid of springs or fluid pressure means, and is based on the principle of measuring the deflective torque on the shank or operating handle of the wrench when applying turning force to a rotatable element. In its preferred construction, my torque indicating wrench comprises a handle provided at one end with means for driving or rotating a cap-screw, bolt, nut, or the like, and has attached to said driving means a rigid arm extending in substantially parallel spaced relation to the handle and having at its opposite end means which operate in conjunction with means carried by and movable with the handle for indicating the deflective torque of the handle under operating load. More specifically, the wrench comprises a gauge mounted on the handle and the rigid arm is made of less length than the handle and provided adjacent the gauge with an oblique shoulder upon which a follower of the gauge is adapted to ride and thereby operate the indicating mechanism of the gauge as the wrench handle is subjected to deflective torque when applying turning force to a rotative element. A preferred embodiment of my invention is illustrated in the accompanying drawing wherein—

Fig. 1 is a top plan view of my torque-indicating wrench.

Fig. 2 is a side elevation of the wrench shown in Fig. 1.

Figs. 3 and 4 are transverse sections taken along the planes of the lines 3—3 and 4—4 respectively of Fig. 2.

Referring to the drawing, the torque-indicating wrench may be said to consist of but three parts, namely, a handle 10, a rigid arm 11, and an indicating gauge 12. The handle 10 at one end is fixedly connected to a driving head 13 which on its under side is provided with a square shank 14 having a spring pressed ball 15 or other conventional means for engaging in and driving a detachable socket (not shown) which is adapted to engage the head of a cap-screw, a bolt or nut, 15 for rotating the same. The opposite end of the handle 10 is formed with a hand gripping portion 16, which may be knurled or otherwise provided with a surface which will promote the gripping engagement thereof. Mounted on the handle, intermediate its ends, and preferably in proximity to the gripping end 16, is a bracket 17 upon which is mounted the dial gauge 12. Preferably the wrench handle will be made of steel and carefully ground to size and specially heat treated and hardened to insure uniformity thereof.

The rigid arm 11 is of less length than the handle and is affixed at one end 17 to the top of the driving head 13 so as to be movable therewith as a unit and extends in overlying spaced substantially parallel relation to the handle 10 and has its other end 18 which is free, disposed adjacent the gauge 12. Intermediate the ends the rigid arm 11 is of arcuate cross section, as best shown in Figs. 2 and 4, and adjacent its free end 18 is 35 formed with a shoulder or flat face 19 which extends obliquely to the longitudinal center line of the arm.

The gauge 12 is rigidly supported upon the handle 10 so that the gauge plunger 20 which is guided for longitudinal movement in the tubular projection 20' of the gauge housing will have its axis substantially coincident with the vertical plane passing through the axis of the handle 10. The free end of the plunger 20 is provided with a follower 21, preferably in the form of a steel ball mounted for free rolling movement within its bearing 21' mounted on the plunger 20 and adapted to ride over the oblique surface 19 at the free end of the arm 11. If desired, the arm 11 at its free end may be formed with an extending finger 22 which will overlie the plunger 20 and serve as a sort of protecting medium therefor. The gauge 12 herein shown is of the dial type and is provided with any well known type of

motion-magnifying means (not shown) which will multiply the movement of the plunger 20 so as to give a larger indication of the pointer 23 on the dial 24.

5 In the use of the wrench hereinbefore described, the shank 14 will engage within and hold a socket member, (not shown) in assembled relation on the driving head. Upon engaging such socket with the head of a cap-screw, bolt, nut or the like, 10 it will be apparent that by gripping the handle at 16 and moving it through an arc with the socket head as a pivot, the cap-screw, bolt or nut will be rotated and thereby fastened onto its complementary part. As the rotatable element, namely, 15 the cap-screw, bolt or nut, is brought up into tightened relation with its co-operating part, it will be apparent that the handle 10 will flex or be deflected under the force of tightening the rotatable element. This deflection in the handle, 20 however, is not imparted to the rigid arm 11, and hence as the arm 10 flexes in moving the handle in a clockwise direction, the follower 21 on the gauge plunger 20 will ride over the oblique face 19, thus moving the plunger inwardly with respect 25 to the gauge housing and said movement will be multiplied and indicated by the pointer 23 on the dial 24. The inch pound or foot pound deflective torque of the wrench can be obtained by converting the indicated dial reading into inch or foot 30 pounds by means of a special conversion table which can be supplied with each wrench. Or the oblique surface 19 upon the free end of the rigid arm 11 can be given such angularity on each wrench that the indicated dial reading at a given 35 load, or deflective torque, will correspond in every case with the proper inch or foot pound torque on the conversion table; or the dial readings may be directly calibrated in inch or foot pounds.

The wrench will be capable of giving an infinite 40 number of accurate readings of deflective torque

so long as the handle is not stressed beyond the elastic limit of the bar stock from which it is made. Even though no conversion table is provided for converting the dial reading into inch or foot pounds, it will be apparent that the wrench will be especially useful in the automotive trade for the purpose of applying equal force to all the cap screws or bolts for tightening down the cylinder head on the engine block or for any other purpose where a uniform tightening of elements is required for a given job by merely tightening the element to the same reading on the gauge.

5 It will accordingly be apparent from the foregoing description that I have provided a torque-indicating wrench of exceedingly simple and durable construction, and while I have shown but a single and preferred embodiment of my invention, 10 I do not wish to be limited to the specific details of construction set forth, since it will be apparent to those skilled in the art that changes in such 15 construction may be resorted to without departing from the spirit of the invention.

What I claim is:

A torque-indicating wrench comprising an operating handle capable of flexing under operating load having at one end driving means for engaging and rotating a rotatable element and intermediate its ends an indicating gauge, a rigid arm fixedly connected at one end to the end of the handle having the driving means and being 25 free at its other end, said arm being of less length than the handle and extending in spaced substantially parallel relation thereto and having adjacent its free end a shoulder which is oblique to the center line of the arm for cooperation with a 30 follower of the gauge for registering on said gauge the deflection of the handle under flexing load when applying turning force to a rotatable element.
